DESIGN FOR A DISPLAY COUNTER

Clinton J. Christopher, Minneapolis, Minn.

Application November 1, 1944, Serial No. 116,095

Term of patent 14 years

(Cl. D80—9)

To all whom it may concern:

Be it known that I, Clinton J. Christopher, a citizen of the United States, residing at Minneapolis, in the county of Hennepin and State of Minnesota, have invented a new, original, and ornamental Design for a Display Counter of which the following is a specification, reference being had to the accompanying drawing, in which

the single figure is a perspective end elevational view of the display counter, the side and end not shown being the same as the similar portions illustrated in the drawing.

I claim:

The ornamental design for a display counter, as shown and described.

CLINTON J. CHRISTOPHER.
